George A. Ayrault, Oakland, and Allison J. McNay, San Carlos, Calif., assignors to California Research Corporation, San Francisco, Calif., a corporation of Delaware

Application November 14, 1951, Serial No. 17,413

Term of patent 14 years

(Cl. D25—1)

To all whom it may concern:

Be it known that we, George A. Ayrault and Allison J. McNay, citizens of the United States of America, residing, respectively, in the city of Oakland, county of Alameda, and in the city of San Carlos, county of San Mateo, both in the State of California, have invented a new, original, and ornamental Design for an Educational Demonstration Device, of which the following is a specification, reference being had to the accompanying drawings, forming a part hereof.

Figure 1 is a perspective view of an educational demonstration device showing our new design.

Figure 2 is an elevational view from the left side of the device, as seen in Fig. 1.

Figure 3 is an elevational view from the front of the device, as seen in Fig. 1.

Figure 4 is an elevation view from the right side of the device, as seen in Fig. 1.

Figure 5 is an elevation view from the back of the device, as seen in Fig. 1.

Figure 6 is a top plan view of the device shown in Fig. 1.

We claim:

The ornamental design for an educational demonstration device, as shown.

GEORGE A. AYRAULT.
ALLISON J. MCNAY.
